UNITED STATES PATENT OFFICE.

EDWIN PYNCHON, OF CHICAGO, ILLINOIS, ASSIGNOR TO THE NATIONAL LUBRICATOR COMPANY, OF SAME PLACE.

CAR-AXLE LUBRICATOR.

SPECIFICATION forming part of Letters Patent No. 368,969, dated August 30, 1887.

Application filed February 7, 1887. Serial No. 226,860. (No model.)

To all whom it may concern:

Be it known that I, EDWIN PYNCHON, a citizen of the United States, residing at Chicago, in the county of Cook and State of Illinois, have invented a new and useful Car-Axle Lubricator, of which the following is a specification.

My invention relates to car-axle lubricators such as are used in car-axle boxes and designed to carry the oil from the bottom of the box to the axle; and its object is to provide a car-axle lubricator which will accommodate itself to the different positions of the axle and to axles in different stages of their use and will be easy to introduce into the box. These objects I accomplish by means of the mechanism illustrated in the accompanying drawings, in which—

Figure 1 is a plan view of my device with the lubricating-roller depressed, so as to lie close to the bottom of the box. Fig. 2 is a side view thereof, showing a broken section of a car-axle box and a portion of the car-axle, and also showing in dotted lines the position which the lubricating-roller would assume in adjusting itself to an axle of different height or one somewhat worn. Fig. 3 is a view of the roller-frame; Fig. 4, a section through the device through the line $x-x$ of Fig. 1. Fig. 5 is an edge view of one of the side pieces of the frame. Fig. 6 is a detail view of the oil-conveyer and agitator-shaft.

Like parts are indicated by the same letter in all the figures.

A A is the base of the lubricator, having the standards B B thereon. The roller-frame is composed of the two side pieces, C C, connected by the bars D D'. The side pieces have each a hook, E, and a stop, F, and also a bearing-slot, G. At one extremity of these side pieces are found the arms H H, in which the cross-bar D is secured, and at the bottom of each of these pieces H are the spring-pockets K. Small lips are formed on the ends of the pieces H H, (marked L L,) and designed to be turned up so as to cover the ends of the spring-pockets K when the springs are in position. Each side piece has a collar, M, a trunnion, N, and a bolt, O, upon which latter is placed the washer P. When the washer P is placed in position, the bolt may be upset, so as to se-

curely fasten the end of the spring which engages the trunnion N. On the bar D' is secured the lubricating-roller Q, which may be constructed as desired; but it is preferably formed with a central core, R, and side disks, S S, and a coil of lubricant-carrier, T.

U is a spiral spring secured at one end to the hook E and at the other to the eye V on the standard B.

W is a wire-spring, which is coiled about the shaft Y, which connects the two standards B B. This spring W is coiled about both ends of the bar Y, and its central portion is downwardly bent, as shown in Fig. 4. Its ends are formed into loops Z, which encompass the trunnions N N.

A' is a roller carrying a spring-coil, B', and provided with the disks C' C', which bear against the disks S S. This roller is loose on the shaft A'', which is provided at its ends with square projections E' E', which slide in the slots G G, and are pressed toward the shaft D' by means of the spiral springs F' F', which rest in the spring-pockets K.

G' is a portion of the car-axle box, and J' J' are car-axles. The washers L' L' are placed on the shaft Y between the ends of the spring W and the standards B B.

Car-axles and their journal-bearings have been generally lubricated by oil distributed by the use of cotton-waste, which, when inserted in the box, carries up the oil by power of capillary attraction, in which way the drops of oil are divided into minute particles, permitting of a considerable loss by evaporation. The waste likewise catches and carries up to the axle the numerous particles of dust and cinder which are ever finding their way into the box when the car is in motion. In this way there is deposited on and between the axle and journal-brass gritty matter which is wearing on both and is often productive of what is known as a "hot box." The waste is also expensive, it being necessary to frequently replace with new that which by use has become clogged with dirt and gummy matter. Furthermore, waste will not so well distribute the cheaper or lower grades of oil, which are thick, as will a mechanical lubricator.

I am aware that many patents have been granted for devices for lubricating car-axles,

a majority of which have depended in whole or in part upon the principle of capillary attraction by the use of one or more wicks, either alone or in combination, as with wheels, revolving brushes, &c., and are therefore, though to a less degree, open to the same objections which have been made to the waste. Lubricators have also been patented composed of one or more rollers. Those in which there is but one roller cannot be used in a box the axle and journal-brass of which have become worn, for while there is but three inches of space beneath the axle of a car-wheel supplied with a master car-builder's standard box 15 when new, this space, by wear of axle and journal-brass, is increased to about four inches before the same is discarded. These boxes are so constructed that the lubricant placed within them should be less than one inch in depth; 20 otherwise there is a loss by leakage through the opening at back of box which allows of the axle entering the same. Consequently, a single roller which would reach from the lubricant to the axle when the latter is worn, as previously described, would be of too great a diameter to be introduced into the box.

My invention, as will be seen above, relates to a purely mechanical lubricator in which an oiling-roller which is supported by spring pressure against the axle and rotated thereby in turn rotates a feed-roller, and thereby carries the lubricant from near the bottom of the box to the axle, working equally as well when the oil is thick as it may be when of low grade or as 35 better oil may become when subjected to great cold. In fact a lubricator of this class will work better with a thick than a thin lubricant, as when the former is used the rapid revolutions of the rollers will not spatter the same 40 to as great a degree.

As explained, in my device a series of two rollers are held in a tilting or cradle frame, which, from projections near its center on either side, is pivotally supported on a spring-frame in such a manner that while the rollers 45 may be pressed down so as to facilitate the easy introduction of the device within the box, they will, when the pressure is removed, assume a nearly vertical position with the oiling- 50 roller above and the feed-roller beneath, and thereby accommodate themselves instantly to even the greatest possible wear of axle, doing away with the necessity of taking any previous measurements in order to secure a lubricator of proper size, as each completed device 55 will fit any axle between the minimum and the maximum conditions of wear, for in either condition, while the oiling-roller is in contact with the axle, the feed-roller is well introduced into 60 the lubricant, which is in the bottom of the box.

I have represented my device with the rollers pressed down so low that they have become parallel and even with the side bars of 65 the bottom frame, as is necessary in order to secure an easy introduction of the lubricator through the door of the box and beneath the

end of the axle, which is an irregular passage, not exceeding two inches in height. This position of the lubricator is also necessarily assumed when in order to remove the journal-brass the car is "jacked up"—a process which elevates the box with the car and causes the axle to relatively descend, so that the space beneath the same, between it and the bottom 75 of the box, is reduced to about two inches, within which space a lubricator must be susceptible of being compressed. In my device the rollers may be pressed down even lower than shown in Fig. 1, so that they project beneath the bottom of bottom frame through the opening therein, thereby better allowing the device to curve around the end of the axle when it is being introduced into the box.

The spring-arms on either side, each acting 85 independent of the other, allow of an oscillating motion of the cradle-frame with the rollers which it supports, so that the oiling-roller will accommodate itself to any variation from the horizontal which the car-axle may make— 90 as when car is rounding curves—and again the easy spring-support will allow of the most rapid compression when in passing over frogs or uneven places in the track the car "jumps," which has the effect of reducing the space beneath the axle in the box.

The lower portion of spring W presses laterally against the upwardly-projecting lug at the side of bottom frame, thus preventing the frame tipping up, and likewise by its pressing bottom of frame against the side of the box it tends to prevent the lubricator changing its position by sliding longitudinally in the box.

The use and operation of my invention are 105 as follows: It will be observed that the frame carries two rollers, one being provided with the lubricant-carrying material T, and adapted to bear against the axle, and the other provided with a spring-coil, B', to descend into 110 the oil-receptacle of the box and keep the oil stirred, and also to assist in forcing it upward against the lubricant-carrier T. The frame which carries these two rollers is supported by two sets of springs—the one W W adapted 115 to lift the entire frame, as shown, the other, U U, adapted to turn the frame on its trunnions N N. The joint action of these two springs is such as to keep the lubricating-roller constantly against the axle and the roller 120 A' constantly in the oil. In the extreme limit of its motion (shown in Fig. 4) the lower roller will be found not greatly elevated above the base of the frame. As the car-axle rotates it causes the lubricating-roller which bears 125 against it to rotate, and this in turn causes the roller A' to rotate, the two sets of disks S S and C' C' being in contact. By this action the oil is carried from the reservoir to the car-axle and thoroughly applied thereto. It is 130 also carried or thrown by the action of the coil B' upon the lubricant-carrier T on the lubricating-roller, and here it is absorbed by the lubricant-carrier, so that the same is kept

constantly supplied with oil. This oil, of course, is continuously transferred to the surface of the axle. The roller A' turns on its axle, the ends of which slide in the slots G, 5 and are elastically held upward by the springs F' F', so as to force the disks of the two rollers together. The action of the lower springs, U U, is to rotate the frame on its trunnions, and thus force the lubricant-carrier against 10 the axle. The action of the springs W W is to raise the entire frame, and thus force the lubricant-carrier against the axle, so that the two springs operate together to keep the lubricant-carrier roller constantly against the 15 axle, no matter how irregular or uneven the motion thereof may be. When the lubricator is out of use, the roller-frame is prevented from turning too far on its trunnions by means of the stops F F', which engage the springs W 20 W, whereas the feeding-roller is always above the bottom of the box. It will not reach the particles of sand and cinder which may get into the box, and which by power of gravitation will sink to the bottom of the oil.

25 I claim—

1. In a car-axle lubricator, the combination of a frame bearing one lubricating and one feeding roller, with arms on which the frame is pivoted, and springs which engage the frame 30 at one side of the pivot, so that when raised or lowered it rotates on its pivots.

2. In a car-axle lubricator, the combination of a base, a frame, two engaging lubricant-carrier rollers pivoted on such frame, spring- 35 arms on which the frame is pivoted, and spiral springs from such frame to the base, so that when the frame rises and falls the rollers rotate about each other.

3. In a car-axle lubricator, an oil-stirring 40 roller provided with a spiral coil of wire spirally applied to same to agitate the oil.

4. In a car-axle lubricator, two lubricant-carrier rollers having end disks which engage, the lower roller being provided with an oil- 45 stirring device which agitates the oil, and the upper roller feeding the oil to the car-axle.

5. In a car-axle lubricator, a frame, in combination with a lubricant-carrier roller pivoted thereon, and a second lubricant-carrier 50 roller and lubricant-stirring roller, the latter roller flexibly held against the former by spiral springs which bear against the ends of the rod which supports it.

6. In a car-axle lubricator, the combination 55 of a frame with lubricant-carrier rollers thereon, spring-arms which support the frame, and lugs on the frame which engage the spring-arms and prevent the frame from turning too far.

7. In a car-axle lubricator, a pivoted frame 60 having an axle-lubricating roller pivoted on one end and provided with slots in its opposite ends, in combination with a rod which is flexibly supported in such slots by spiral springs, and an oil stirring and carrying lubricator which rotates on such rod. 65

8. In a car-axle lubricator, a lubricating mechanism consisting of two rollers supported longitudinally in a tilting cradle-frame, which from lateral projections from near the center 70 thereof on either side is pivotally supported, so that when rotated on its pivots one roller ascends and the other descends.

9. In a car-axle lubricator, a lubricating mechanism consisting of two rollers supported longitudinally in a pivotally-swinging frame, as described, the upper roller revolving on a rigid axle, while the lower roller is provided with an axle whose flattened ends slide freely in a slot on either side, so that the 80 two rollers can be made to come in apposition, said axle being provided with spring-bearings which tend to push the same toward the opposing roller. 75

10. In a car-axle lubricator, a lubricating 85 mechanism consisting of two rollers supported longitudinally in a tilting frame, which from lateral projections on either side has a free pivotal support on independent spring-arms and provided on either side below the pivotal 90 point with compensating spiral springs the opposing ends of which are attached to a rigid portion of the bottom frame, so that the tendency of the tilting frame is to assume a vertical position and an upward motion. 95

11. A car-axle lubricator consisting of two or more rollers, the most dependent of which being a feed-roller with wide disks at either end and supplied with a spiral coil loosely and spirally applied thereon, as shown. 100

12. A car-axle lubricator provided with a main frame having the standards B B thereon, a lug at the rear and between the standards, and a connecting cross-bar, Y, in combination with the lubricator-frame bearing the lubricating-rollers, and a spring-support, W, which is secured at each end to the pivotal point of the lubricator-roller frame, is then wrapped around both ends of the rod Y, and passes downward in the form of a loop, which engages the lug on the rear of the frame, as and for the purpose shown. 105

EDWIN PYNCHON.
